APPARATUS FOR USE IN CONNECTION WITH
THE MAKING OF BAGSAdolph Potdevin, Garden City, N. Y., assignor to
Potdevin Machine Company, Brooklyn, N. Y., a
corporation of New YorkOriginal application April 22, 1932, Serial No.
606,839. Divided and this application September
29, 1934, Serial No. 746,083

5 Claims. (Cl. 112—10)

This invention is directed to an improved apparatus for use in connection with the making of paper bags, being primarily directed to an apparatus for folding a paper tape over the ends 5 of a bag and stitching the same in place, the tape being supplied in a continuous strip from a supply roll and advanced successively to an apparatus for sewing the tape along the ends of the bag.

10 In the drawings accompanying this application:

Fig. 1 is a side elevational view of my improved apparatus;

Fig. 2 is an end view of the apparatus substantially along the line 2—2 of Fig. 1;

Fig. 3 is a plan view;

Fig. 4 is a detail of one of the pushers employed for advancing the bag to the sewing apparatus;

Fig. 5 is a detail of the folding apparatus for 20 the paper tape;

Fig. 6 is a section on the line 6—6 of Fig. 7;

Fig. 7 is a plan view of the apparatus of Fig. 5;

Fig. 8 is a detail of the cutting mechanism;

Fig. 9 is a view substantially on the line 9—9 of Fig. 3;

Fig. 10 is a view substantially on the line 10—10 of Fig. 3;

Fig. 11 is another view of the cutting mechanism; and

Fig. 12 is a plan view of the bags with paper strips sewn across the ends thereof.

Referring to the drawings in detail: The machine of this invention comprises a feed table 1 elevated at a convenient distance above the floor, the bags being advanced successively along this table to a pair of sewing machines intermediate the ends of the machine. These sewing machines are well known commercial apparatus and will not be described in any detail. They are designated 2 and 3 on the drawings.

40 The paper tape which I fold over and stitch to each end of the bag is taken from rolls 4 and 5 at opposite sides of the machine and the thread employed for sewing this tape to the bags is taken from bobbins 6 and 7 also at opposite sides of the machine. Pivoted to the bottom of the frame 8 of the machine are vertically extending pusher arms 9. Two or more of these arms are provided and the arms are adjustably affixed to a rock shaft 10 mounted in the lower part of the machine frame.

45 The table 1 of the machine is slotted longitudinally as shown at 11 and 12, for instance, in Fig. 3, and on the upper ends of each of the pusher arms 9 is pivoted a pusher 13 which under certain conditions projects above the top of the table through the slots above mentioned. Each 50 of these pushers is provided at its rear end with a spring 14, the lower end of this spring being attached to a pin 15 on the pusher arm.

Each pusher is provided with a roller 16 at its forward end, these rollers riding along the underside of the table 1 of the machine on movement of the pushers to the left, or in a forward direction, as viewed in Figs. 1 and 4, for instance.

5 Near the end of their travel the rollers 16 engage the forward end of a rail 17 resiliently mounted below the table 1. The rail is held in its upward position as shown in full lines in Fig. 4, for instance, by spring 18. On reversal 10 of the pushers after they reach the limit of their forward movement, the rollers 16 ride along the underside of the rail 17 so as to retract the pushers out of the slots 11 and 12 entirely, the pushers pivoting to their original position, however, under 15 the action of the springs 14 as soon as they ride off the rear or tail end of the rail 17 so that on the next forward movement of the pushers the rollers will travel along the upper side of the rail with the pushers projecting through the slots 11 20 and 12 as before.

The rocker rod 19 carrying the pusher arms 9 is rocked through the medium of an arm 20 the lower end of which is fast to the shaft 10. A link 21 is adjustably secured to the upper end of the arm 20 by a slot and bolt connection 22 and 23, the other end of this link being attached to crank 24. The drive for the crank 24 will be referred to hereinafter.

The adjustable connection of the link 21 to the arm 20 enables the travel or throw of the pushers 30 to be varied so as to accommodate the machine to bags of different widths, it being appreciated that the bags are fed forward to the sewing machines laterally as distinguished from 35 lengthwise.

As the bags are advanced by the pushers 13 they pass under hold-down plates 25 adjustably mounted, as will be brought out hereinafter.

At each side of the machine I provide means 40 for applying paper tape to the ends of the bag, the tape being stitched to the bag ends as the bags progress through the machine.

The paper tape, as has already been mentioned, is taken from supply rolls 4 and 5 which are 45 mounted on suitable standards at each side of the machine. Each tape as it passes into the machine travels over the face of a gluing roller 26 where glue is applied to the edge of the paper as shown in Fig. 2, for example, the paper tape being designated 27 and the adhesive 28. After 50 each of the paper tapes receives its coating of adhesive it passes around a roller 29 set at an angle of 90° to the plane of the paper and from thence the paper tape passes into a trough-shaped folding member 30, this member, as seen in Fig. 7 for instance, gradually decreasing in 55 width until at the discharge end thereof it is just about the width of a double thickness of the tape and the thickness of the bag.

45

50

55

60

Extending into this trough-like folding member is a guide plate 31 spaced from the top of the member 30, the tape passing between this plate 31 and the inner face of the member 30.

5 Extending into each of the folding members 30 is a plate 32 providing a guide plate for the bag, which in Fig. 5 I have designated 33, the bags as they are advanced through the machine passing along the side of this guide plate 32.

10 As the paper tape leaves the roller 29 it is flat and at right angles to the end of the bag. As the bag and tape advance through the folder or former 30 the tape is folded over the bag end to emerge from the folder as is indicated in 15 Fig. 5.

The hold-down plates 25 are adjustably mounted at the underside of a slotted bar 35 extending transversely of the machine and fastened at each end to the side frames of the machine. Each 20 plate is held to this bar by a bolt 36, passing through the slot in the bar, and a nut 37. It will be appreciated that this permits of each plate being adjusted laterally independently of the others.

25 The rollers 29 are adjustably supported on the transverse bar 35 by brackets 38 and bolts and nuts 39. These brackets 38 also support the trough-like members 30, the brackets being provided with a strap 40 which may be secured to the member 30 in any suitable manner.

The members 32 above referred to are adjustably carried by the transverse bar 35, being attached thereto by a bolt 41 and nut 42.

30 The plates 31 heretofore referred to which lie 35 within the trough-shaped members 30 are carried by guide plates 45 extending longitudinally of the machine along each side thereof, these plates 45 properly directing the end of the bag into the apparatus as the same progresses into that part 40 of the machine where the tape is applied to the bag ends. These plates are set so as to hold the bags away from the tape until both bag and tape have moved into that part of the machine where the tape is applied. The plates 45 are held 45 in place on the machine frame by thumb screws 45'. One of the plates 45 is capable of being adjusted transversely of the machine to accommodate the machine to bags of different lengths by providing a plurality of holes 45'' for receiving the thumb screws.

50 It will be appreciated, therefore, that the rollers 29, brackets 38 and member 30 are adjustable as a unit; also that guide plates 45 and plate 31 are adjustable as a unit independently of the rollers 29, brackets 38 and member 30 and that the plate 32 is likewise adjustable independently of each of these members.

The base of each of the sewing machines 2 and 3 is designated 46 and is adjustable transversely of the machine, being mounted in guideways 47 so that the machine may be adjusted transversely of the machine to accommodate bags of different lengths.

55 The bags as they pass from the sewing machines travel between feed rollers 48 and 49, 50, 51 and 52, 53, the latter discharging the bags upon a receiving platform 54. The rollers 48, 50 and 52 are adjustably mounted on shafts 55, 56 and 57, respectively; while the rollers 49, 51 and 53 are adjustably mounted on shafts 58, 59 and 60, respectively.

70 One set of rollers 48 and 49 is adjustable with adjustment of the sewing machine base on that side of the machine, the bearing for the shafts

55 and 58 which carry the rollers 48 and 49 being provided in a member 58' which is rigid with the base of the sewing machine.

The rollers 48 and 49 travel slightly faster than the machine feed so as to exert a gentle pull on the paper. Likewise the rollers 50 and 51 travel slightly faster than the rollers 48 and 49 to keep the paper taut, while the rollers 52 and 53 are further overspeeded to effect quick discharge.

10 Intermediate the sets of feed rollers 48, 49 and 50, 51 is the cutting-off mechanism 61 for the tape.

15 Reference numeral 90 designates a shaft extending transversely of the machine and mounted at each end in suitable bearings 91. On each end of this shaft is a bevel gear 92, adjustable on the shaft and meshing with bevel gear 93 on the outer end of a stub shaft, each of these stub shafts carrying a cutter 61 at its inner end. 20 The cutters are operated intermittently to sever the paper tape adjacent the side of each bag after the tape has been sewn in place thereon.

25 At one end the shaft 90 is provided with a bevel gear 94 in constant mesh with two pinion bevel gears 95 which are mounted in a rotatable housing 96.

30 Reference numeral 97 is a stub shaft extending through the housing 96 and carrying a bevel gear 98 in mesh with the pinions 95. By this differential arrangement if the housing 96 is held against rotation, rotation can be imparted to the shaft 90, while on the other hand if the housing is permitted to rotate no rotation will be imparted to this shaft.

35 The shaft 90 carries a ratchet 99 cooperating with pawl 100.

40 At its inner end housing 96 is provided with ratchet 101 adapted to cooperate with pawl 102. The two pawls are pivotally mounted on stationary mount 103 and are connected to each other for simultaneous operation by bar 104. When one pawl is in engagement with its ratchet the other pawl is out of engagement with its 45 cooperating ratchet.

45 The connecting member or bar 104 is pivoted to one arm 105 of a bell crank lever which is pivoted to the mount 103. The other arm of this bell crank lever is pivotally connected to a link 106 the opposite end of which is pivotally 50 connected to one arm 107 of a bell crank lever pivoted on the machine frame, the other arm 108 of this bell crank lever being connected through a link 109 with a cam follower 110 cooperating with cam 111 on the same shaft 71 with the 55 crank 24 which drives the pusher mechanism for the bags as above described.

55 It will be seen that when the cam 111 is rotated the pawls 100 and 102 will be actuated intermittently alternately to release ratchet 99 and 60 lock ratchet 101.

65 At the side of the machine opposite the differential just described bearing members 113 and 114 are attached by member 115 to the sewing machine base 46. Accordingly adjustment of the sewing machine will at the same time and to the same degree effect adjustment of the rollers 48 and 49 and the cutting mechanism adjacent thereto.

70 The driving motor for the machine is designated 62 and the shaft of this motor is provided with a gear 63 meshing with a gear 64 in mesh with a gear 65 on a shaft 66 carrying a worm 67. This worm meshes with a worm gear 68 on a short shaft carrying a bevel gear 69 meshing 75

with bevel gear 70 on the shaft 11 carrying the crank 24.

The shaft 72 carrying the gear 64 also carries a gear 73 meshing with gear 74 on the shaft 5 of 58 of the feed roller 49. This shaft 58 carries a gear 75 meshing with gear 76 which is on the shaft 97.

The gear 74 also meshes with an intermediate gear 78 meshing with gear 79 on the shaft 59 of 10 the feed roller 51, the gear 79 in turn meshing with an intermediate gear 80 meshing with a gear 81 on the shaft 60 of the feed roller 53.

The shaft 72 which carries the gear 64 is provided at its other end with a gear 82. The gear 15 64 meshes with a small gear 83 while the gear 82 meshes with a small gear 84, the gears 83 and 84 being the drive gears of the two sewing machines. The shaft 72 which carries the gears 64 and 82 extends entirely across the machine.

Reference numeral 85 designates a sleeve on 20 the shaft 72 adjacent the gear 82 which drives sewing machine gear 84, this sleeve being carried by a hanger 86 attached to the sewing machine base 46. Inside the sleeve 85 is a headed bushing 25 keyed to the shaft 72. This bushing passes through the gear 82 and the hub of the latter is secured thereto as by a screw, for instance. Consequently when the sewing machine base 46 is adjusted gear 82 will be adjusted and hence 30 remain in mesh with the sewing machine gear 84.

Adjustment of the sewing machine base 46 and the rollers 48 and 49 is effected by a threaded rod 87.

In operation the bags are fed successively to 35 the table 1 and advanced by the pushers 13 to the sewing machines 2 and 3. As the ends of the bags enter the forming members 30 they pass between the plate 32 of each of these members 40 and the side of the forming member, the guide plates 31 properly directing the bag. The tape from the rolls 4 and 5 is advanced with the bags, passing through the forming members 30 where 45 it is folded over the ends of the bag, the tape previously having been glued at the rollers 26. As a consequence when the bag reaches the sewing machines 2 and 3 the tape has been folded over the bag ends and pasted down.

As the bags pass through the sewing machine 50 the tape is sewn in place and by the time this sewing operation is completed the cam 111 has moved to such position that the pawl 102 will be in engagement with the ratchet 101 to prevent the housing of the differential mechanism 55 which constitutes a part of the drive for the cutters from rotating. Consequently the pinion 94 will be driven to drive the shaft 90, rotating the cutters 61 and severing the tape. The rotation of these cutters is only momentary, further 60 rotation of the cam 111 shifting the pawl 102 out of engagement with the ratchet 101 and the pawl 100 into engagement with the ratchet 99, this latter operation preventing further rotation of the cutters without, however, necessitating stopping the gear 76. The bag is then passed by the 65 feed rollers 50, 51, 52, 53 to the discharge platform 54.

It will be appreciated that by changing the worm gear 68 the machine can be changed over 70 to accommodate bags of different widths.

It will be understood that changes may be made in the mechanism above described within the purview of my invention.

This application is a division of my copending application Serial No. 606,839, filed April 22, 1932 which has resulted in Patent No. 1,989,943.

What I claim is:—

1. In apparatus of the class described, the combination of means for advancing articles successively along a support, means in the path of the articles for folding tape over the ends of the articles and to secure the same in place to provide a plurality of advancing articles connected by the tape, a drive for the advancing means operating continuously, rotary cutters for severing the said tape between adjacent articles, driving mechanism for the cutters, and cam mechanism between the cutter driving mechanism and the driving mechanism for the advancing means and controlled by the latter to effect intermittent rotation of the cutters.

2. In apparatus of the class described, the combination of means for advancing articles successively along a support, means in the path of the articles for folding tape over the ends of the articles and to secure the same in place thereby to provide a plurality of advancing articles connected by the tape, a drive for the advancing means, said drive operating continuously and comprising a crank, rotary cutters for severing the said tape between adjacent articles, driving mechanism for the cutters, and a cam affixed to the shaft of said crank for effecting intermittent and timed rotation of the cutters.

3. In apparatus of the class described, the combination of pusher mechanism for advancing articles successively along a support, means in the path of the articles for folding tape over the ends of the articles and to secure the same in place thereby to provide a plurality of advancing articles connected to each other by said tape, a driving motor, a crank driven by said motor for driving the pusher mechanism, forwarding rollers driven by said motor for continuing the advance of the connected articles, rotary cutters for severing the tape between adjacent articles, and a cam rotating in fixed relation to said crank for effecting intermittent rotation of said cutters.

4. In apparatus of the class described, the combination of pusher mechanism for advancing articles successively along a support, means in the path of the articles for folding tape over the ends of the articles and to secure the same in place thereby to provide a plurality of advancing articles connected to each other by said tape, over-speeded forwarding rollers for receiving the connected articles, rotary cutters for severing the tape between adjacent articles, and cam mechanism driven in timed relation to said pusher mechanism for intermittently rotating said cutters.

5. In apparatus of the class described, the combination of mechanism for advancing articles successively along a support, means in the path of the articles for folding tape over the ends of the articles and to secure the same in place thereby to provide a plurality of advancing articles connected to each other by said tape, rotary cutters for severing the tape between adjacent articles, cam mechanism to effect intermittent rotation of said cutters, and pairs of rollers at each side of said cutters operating at different speeds to maintain tension on the tape during the severing operation.

ADOLPH POTDEVIN.
